UNITED STATES PATENT OFFICE.

ELMER A. SPERRY, OF BROOKLYN, NEW YORK.

ELECTRIC HEATER.

1,116,855.

Specification of Letters Patent. Patented Nov. 10, 1914.

Application filed January 4, 1908. Serial No. 409,359.

To all whom it may concern:

Be it known that I, ELMER A. SPERRY, a citizen of the United States, residing at Brooklyn, in the county of Kings and State of New York, have invented new and useful Improvements in Electric Heaters, of which the following is a specification.

My invention relates to electric heaters and consists in sectional details organized to quickly convey heat away from an electric conductor by convection, through the medium of a fluid which is preferably a non-electrically conducting fluid.

It also relates to means for receiving and transforming the heat thus developed into the useful form of energy, such for instance as utilizing it for developing steam pressures within the steam generator.

It further consists in various structural details more fully described in the accompanying application and pointed out in the claims.

The accompanying drawings serve to illustrate one form in which my invention may be carried into practice:

Figure 1 of the drawings, illustrates a side elevation, partially in diagram, of my electric heater or steam generator. Fig. 2 is a sectional view of the same. Fig. 3 a sectional view of one of the flues or tubes within the generator. Fig. 4 shows the sectional support of the electric conductors. Fig. 5 shows a detail of their arrangement, giving the electrical conductors in section.

The characters of reference indicate like parts throughout the several views.

The object sought by my invention is to improve electric heaters securing therein low temperatures of the conductors and equalizing the temperatures of all parts of the conductors. Furthermore, to provide a heat transmitting medium which will not be affected by the inevitable expansion and contraction of the conductors themselves. Also, means whereby the heat may be very rapidly carried away from the conductors, thus yielding an apparatus of great capacity as compared to size, and operation of the electrical conductors under seal, thereby effecting absence of oxidation.

In all electric heaters of this class, the materials used in conducting heat from elec-

trical resistances have heretofore been essentially heat transmitters, whereas the present invention has to do with heat carriers, which are found to be very much more active and efficient. The difference is four fold and very important. First, for obtaining a given temperature at the outer wall of the heating compartment, it is necessary that the electrical conductor be maintained at a very high temperature. Secondly, the heat conductivity of neutral bodies is at best very low, requiring large surfaces to be exposed. Thirdly, for obtaining a given result the apparatus must be much larger, more cumbersome and expensive. Fourth, there must be automatic safety devices provided against over heating of the conductor or the conducting media. The fact is where an organization exists for causing positive convection currents of the media, the phenomena may be characterized as active, whereas the heat transmitters are all simply passive.

A further object of my invention is to greatly cheapen and lessen first cost of the apparatus and render same perfectly safe owing to the low maximum temperatures employed, even where high pressures of steam are generated.

The boiler shell 7 is provided with the usual legs or supports 8-8 and the steam dome 9. The ends of the boiler are pierced with the usual apertures for the flues 10 shown in Fig. 2, their arrangement being preferably in rows so placed vertically that the tubes will be over the spaces between those below. These tubes may be open-ended and extend into the crown sheets 12 in the usual manner. The tubes are grouped leaving a lateral space on either side from which the tubes are separated by guide plates or dams 11, which may be grooved or otherwise, as the case may be.

In Fig. 4 is illustrated one of the sections of the support of the electrical conductor. These sections are provided with extensions or supports 13 and consist preferably of insulating material, vitreous material being preferred. The supporting segments 13 are seen laterally disposed in Fig. 3 where they rest upon the inner walls of one of the tubes 10; the various sections of the support are

connected with each other by the mortise and tenon 14 and consist in two semi-circular ribs 15 15, preferably grooved to receive the conductors, with each alternate groove of 5 larger radius of curvature as it passes to the center, connected as shown in Figs. 3 and 4, at 16—16, etc.

The conductors 17 are shown lying close to each other but not in contact as they pass 10 over the edge of electrical supports 15—15 but inasmuch as every other wire lies in a groove 18, it crosses the space between the supports 15 nearer the center that its neighbor which rests upon the elevation of larger 15 segment 16. It thus happens that across the top the wires 17 are arranged as seen in Fig. 5, being well separated, the spaces between them being for the purposes now to be explained.

20 The bridge 19 which couples the two side portions 15—15 is pierced longitudinally, as shown by dotted lines at 20 in Fig. 3, as is also the tenon at the end, the hole registering with the aperture 20, shown in section in Fig. 4. This aperture is provided for the purpose of returning the last end of the coil through the center to the beginning so that both ends of the coil may be available for the connections, with the controller 25 or switch 21 shown in Fig. 1 at 22, all contained within the hoods 23, which are shown at the other end of the bar in Fig. 1, provided with the pressure gage 24 and draw-off 25. This inclosure communicates with 30 all of the flues or tubes 10 and these are filled with a fluid, the level of which is indicated at 26. This fluid may be a gas or liquid, the latter being preferable, and may be under any desired pressure, thus securing 35 any required degree of physical contact between the convexing fluid and the heating conductors 17, and also the walls 10 of the inclosure, thus aiding in the heat transfer and also in the rapidity with which it is 40 transferred to the convexing fluid, as for instance the water 27 outside the walls 10. When liquids are used, insulating liquids such as high boiling point oils, parafins or compounds are preferred. As is well known, such 45 liquid should have as high a specific heat as possible and also possess as great fluidity as is compatible with the temperatures present. Any means may be employed to create pressures within the circulating medium or the natural hydrostatic pressures owing to the heat—see liquid levels 26 in 50 Fig. 1—may be employed.

It will be understood that the fluid in contact with the electrical conductors 17 may 55 circulate freely upwardly between supports 15—15, sweeping the near walls of the inclosure or tube 10. The heat is delivered through said walls and the cold fluid flows downwardly outside the supports 15 and in

contact with the walls, the two streams having 65 intermingled again passing upwardly through the openings between the bridges 19, plainly shown in Figs. 3 and 4.

The operation of my electric heater involves an enormous saving of the heating 70 surface per boiler H. P. over an ordinary boiler, actual calculations based on certain heat transferring mediums, such as oil, showing that my boiler need be but $\frac{1}{10}$ to $\frac{1}{2}$ the size of the ordinary boiler and besides 75 with my apparatus a greater safety and cheaper cost of construction is obtained and the absence of oxidation by operating under seal, the excellent contact between the heating and heated media, circulation of the 80 transferring medium and low temperature of the conductors render the device when used extremely efficient, durable and advantageous when compared with heretofore known devices of similar nature.

It will readily be understood that this apparatus may be employed to equalize temperatures of electrical conductors and for purposes other than the generation of steam which is employed herein to illustrate one of 90 its uses.

In connection with the drawings serving to illustrate one embodiment of the invention, while it is desired to use various parts in other relations shown, yet it will readily 95 be understood that alternate ends may be employed and some portions may be omitted and others substituted and the invention extends to such use.

I claim:

1. In an electric heating device a reservoir containing a fluid, a plurality of inclosures containing a second fluid submerged in the first, heating conductors in the last named fluid and a structure associated with the conductors for allowing positive convection currents in the last named fluid.

2. In an electric heating device a reservoir containing a fluid, a plurality of horizontal tubular inclosures containing a second fluid submerged in the first, heating conductors in the last named fluid and a structure associated with the conductors for allowing positive convection currents in the last named fluid.

3. In an electric heating device a reservoir containing a fluid, a plurality of inclosures containing an electrically insulating fluid submerged in the first, heating conductors in the last named fluid and a structure associated with the conductors for allowing positive convection currents in the last named fluid.

4. In an electric heating device a reservoir containing a fluid, a plurality of inclosures containing a fluid of high specific heat and fluidity submerged in the first, heating conductors in the last named fluid

and a structure associated with the conductors for allowing positive convection currents in the last named fluid.

5. In an electric heating device a reservoir containing a fluid, a plurality of inclosures containing a fluid under superatmospheric pressure submerged in the first, heating conductors in the last named fluid and a structure associated with the conductors for allowing positive convection currents in the last named fluid.

6. In an electric heater, a unitary electric heating element, comprising an inclosure and electric conductors so arranged within said inclosure as to allow fluid within the inclosure to repeatedly circulate among the conductors and within the inclosure.

7. In an electric heater, a unitary electric heating element, comprising an inclosure and electric conductors so arranged within said inclosure as to allow fluid within the inclosure to circulate upwardly among the conductors and downwardly outside the conductors.

8. In an electric heater, a unitary electric heating element comprising an inclosure and electric conductors so arranged in said inclosure as to allow fluid within the inclosure to circulate upwardly in the central portion of the inclosure and downwardly near the walls of the inclosure, whereby a rapid transfer of heat is obtained.

9. In an electric heater, heating conductors surrounded by a fluid within an inclosure and a structure associated with the conductors for allowing the fluid to circulate upwardly among the conductors and downwardly on each lateral side thereof, exterior to the support for the conductors.

10. In an electric heater, a heating coil and spaced supports on which said coil is so wound that adjacent loops of the coil are spaced a greater distance apart between said supports, than upon said supports.

11. In an electric heater, a heating coil and spaced supports on which said coil is so wound that adjacent loops of the coil are spaced a greater distance apart between said supports, than upon said supports, and a perforation through said supports.

12. In an electric heater, a heating coil, parallel supports therefor upon which said coil is wound so that the adjacent loops of the coil are spaced a greater distance apart between said supports than where they rest on said supports at each quarter loop of said coil.

13. In an electrically heated boiler, the combination, with a liquid receptacle, of tubes passing therethrough, an electric heating device contained in said tubes, and means for producing fluid circulation between said heating devices and the walls of said tubes.

In testimony whereof I have hereunto set my hand in presence of two subscribing witnesses.

ELMER A. SPERRY.
